(57) CLAIM

The ornamental design for a garment with hand coverings, as shown and described.

DESCRIPTION

FIG. 1 is a front elevation view of a garment with hand covering showing my new design;

FIG. 2 is a back elevation view thereof;

FIG. 3 is a front elevation view of a second embodiment of a garment with hand coverings showing my new design; and,

FIG. 4 is a rear elevation view thereof.

The broken lines shown in the drawings depict portions of the garment with hand covering that form no part of the claimed design.
